LUBRICATING SYSTEM AND APPARATUS

Filed Nov. 11, 1927

UNITED STATES PATENT OFFICE

ERNEST W. DAVIS, OF OAK PARK, ILLINOIS, ASSIGNOR TO ALEMITE CORPORATION, OF CHICAGO, ILLINOIS, A CORPORATION OF DELAWARE

LUBRICATING SYSTEM AND APPARATUS

Application filed November 11, 1927. Serial No. 232,549.

My invention relates to lubricating systems and apparatus suitable for lubricating a plurality of bearings from a single source, and more particularly to an improved conduit arrangement whereby the operation of the system may be readily observed.

It is an object of my invention to provide an improved measuring valve system for lubricating a plurality of bearings, in which an indication of the completion of the operation of the measuring valves in the system is readily observable to the operator.

A further object is to provide a fitting for use in a progressive or series lubricating system in which the necessity for one of the measuring valves is eliminated and which makes possible an indication, at the point where the lubricant is supplied to the system, to apprise the operator that sufficient lubricant has been forced into the system.

Other objects will appear from the following description, reference being had to the accompanying drawing, the single figure illustrating the system of my invention as used with three bearings, portions of the apparatus being shown in section.

While I have shown my invention as applied to three bearings, it will be understood that the system is designed for lubricating any number of bearings and that the three shown are thus to be considered as illustrative of a larger number. The present invention is a modification of the system and apparatus shown in my co-pending application, Serial No. 219,837, filed September 16, 1927.

In the drawing I have shown a system of my invention applied to three bearings, 2, 4, and 6, which may be located some distances apart on the machine to be lubricated. A double L fitting 8 is threaded in the bearing 2 and has a laterally extending boss 10 which is adapted to receive a high pressure lubricant receiving nipple 12, which is illustrated as having a transverse coupling pin 14, and which is customarily referred to as a "pin fitting". The nipple also has a spring pressed ball closure 16 which is adapted to seal the opening in the end of the bore which extends longitudinally of the nipple and which communicates with the L shaped duct 18 in the

fitting 8. Duct 18 is connected by conduit 20 to a measuring device 22 threaded in bearing 4. This measuring device is fully disclosed and claimed in my co-pending application above referred to and will be but briefly described herein.

The measuring device 22 comprises an axially bored body 24 closed by a head 26 to which the conduit 20 is connected in any suitable manner. A piston valve 28, having a hemispherical knob 30 at the center of its top, is freely reciprocable within the bore of the body 24 and is normally pressed upwardly by a spring 32, with its knob 30 closing a passage 34 formed in the head 26. A gasket 36 is positioned at the lower end of the bore of the body 24 and forms a seat for the lower edge of the skirt portion of the piston valve 28. There is sufficient clearance between the skirt portion of the valve 28 and the cylindrical bore in which it is adapted to reciprocate to permit slow passage of lubricant. This clearance is exaggerated in the drawing. An outlet passage 38 is adapted to be connected by a conduit 40 to the measuring device associated with the next bearing of the series to be lubricated, here illustrated as leading to the measuring device 22' which is threaded into bearing 6. The measuring device attached to the last bearing of the series to be lubricated (here illustrated as 22') is connected by a conduit 42 to the L shaped duct 44 in the fitting 8, which duct leads to the first bearing 2 of the series.

Assuming that all of the measuring valves and conduits are filled with a lubricant such as grease or oil, and the piston valves 28 of the measuring devices 22 and 22' are at the upper end of their strokes with their knobs 30 sealing the inlet passages 34, the operation of the system will be as follows. A suitable lubricant compressor is coupled to the pin fitting 12 and lubricant forced into the system under high pressure. As soon as the pressure is built up sufficiently to overcome the pressure exerted by the spring 32 of the device 22, the valve 28 will be forced downwardly. Since the area of the knob 30, which is the only portion of the valve initially exposed to the lubricant pressure, is very much

smaller than the total area of the top of the piston valve 28, a much greater pressure will be necessary to start movement of the valve 28 than will be required to continue forcing it downwardly after the entire top surface of the piston valve is exposed to the lubricant under high pressure. The valve will thus have a rapid downward movement making it impossible for any appreciable quantity of lubricant to by-pass around the valve 28 to the bearing, but instead, all of the lubricant beneath the valve 28 will be forced under high pressure into the bearing 4. When the valve reaches the lower end of its stroke, its skirt portion will seal against the gasket 38 thus to prevent the possibility of lubricant leaking past the valve to the bearings.

As the valve 28 approaches the lower end of its stroke it uncovers the outlet port 38, permitting lubricant to flow through the conduit 40 to the next measuring device (22') of the series. Since it requires a much greater lubricant pressure to unseat the piston valve in the measuring device 22' than to maintain the valve 28 of the measuring device 22 at the lower end of its stroke, the latter valve will remain seated upon this gasket 36 until the pressure is relieved. The device 22' will, of course, operate in a manner similar to that described with reference to device 22, as will any number of the devices which may be connected in series. The last device of the series, here illustrated as device 22', connected by the conduit 42 to the fitting 8, will permit passage of lubricant to this conduit and hence to the passage 44 to the bearing 2. The operator will watch the bearing 2 as he forces lubricant into the nipple 12 and as soon as grease is extruded from this bearing will have a visual indication that sufficient lubricant has been supplied to the system and that all of the measuring devices have operated satisfactorily. If desired the shaft in the bearing 2 may have a groove 46 cut in its surface (or the groove may be in the bearing) to aid in permitting passage of lubricant to that end of the bearing adjacent the pin fitting 12 or such groove may be cut in the surface of the bearing. When pressure is released the valves 28 will be forced upwardly by their springs 32, permitting the lubricant to by-pass around the valves to the space thus formed beneath them.

While I have shown and described but one embodiment of my invention, it will be apparent to those skilled in the art that variations thereof may be made without departure from the principles of the invention. For example, the measuring valves may be made of different sizes to supply different quantities of the lubricant to the various bearings as they may require, and different types of measuring devices may be substituted in the system. I therefore desire the scope of my

invention to be limited only by the claims which follow.

I claim:

1. In a lubricating system of the class described, the combination of a plurality of machine bearings to be lubricated, a series of measuring devices adjacent each except one of said bearings, each of said devices being adapted successively to supply a measured quantity of lubricant to its associated bearing and uncover a passage to the next device of the series, and a fitting attached to one of said bearings, said fitting having means for receiving lubricant under high pressure and having a passage leading therefrom to the first device of the series and a second passage leading from the last device of the series to the bearing associated with the fitting whereby the completion of the operation of the system will be indicated by the extrusion of lubricant from the bearing adjacent the fitting through which lubricant is supplied to the system. 70
75
80
85
2. In a system of the class described, the combination of a plurality of bearings to be lubricated, lubricant apportioning devices associated with said bearings, conduits connecting said devices in series, and a fitting attached to one of said bearings and taking the place of one of said devices, said fitting comprising means for making a quick detachable connection with the source of lubricant under pressure, means for connecting said last named means with the first device of the series and connecting the last device of the series with the bearing to which the fitting is attached whereby the completion of the operation of said devices may be indicated by the extrusion of lubricant from said last named bearing. 90
95
100
105
3. In a system of the class described, the combination of a plurality of bearings to be lubricated, series connected lubricant apportioning means associated with each of said bearings except one, and a fitting attached to said one bearing and having two independent passages therein, one of said passages forming a portion of the conduit leading from the source of lubricant supply to the first device of the series and the other leading from the last device of the series to the bearings to which the fitting is attached. 110
115
4. A fitting for use in a series progressive lubricating system comprising a body having one end threaded for attachment to the first bearing of the series to be lubricated, two separate passages in said fitting, a nipple adapted to receive lubricant under pressure communicating with one of said passages, means at the other end of said passage for making a connection with a conduit leading to the second bearing of the series, and means at one end of the second passage for making a connection with a conduit leading from the last bearing of the series, the other end 120
125
130

of said second passage leading from said threaded end of the fitting.

5. A fitting for use in lubricating systems comprising a body having two separate passageways therethrough, means to supply lubricant under pressure to one of said passageways, means to connect the other passageway to a part to be lubricated, and means to connect said passageways with lubricant transmitting conduits.

10. 6. In a system of the class described, the combination of a plurality of bearings to be lubricated, series connected lubricant apportioning means associated with said bearings, 15 and a fitting having two independent passageways therein, one of said passageways forming a portion of the conduit leading from a source of lubricant supply to the first device of the series and the other passageway being connected to the last device of the 20 series.

In witness whereof, I hereunto subscribe my name this 4th day of November, 1927.

ERNEST W. DAVIS.
